UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

RAILWAY-CAR TRUCK.

Application filed May 21, 1927. Serial No. 193,343.

This invention relates to railway car trucks.

An object of the invention is to provide a railway truck of the pedestal type wherein the principal load is imposed upon the truck frame proper and transmitted to the journal boxes through the medium of bars, one of which is pivotally connected to each pedestal of the truck, with one end of the same bearing upon the journal box and the opposite end thereof bearing against yieldable means supported by the pedestal, the construction being arranged so as to positively control the movements and positions of the journal box in its pedestal in order to maintain the same in proper alignment and prevent excessive tilting of the box about the axis of the journal.

Other and further objects of the invention will more fully and clearly appear from the description and claims hereinafter following.

In the drawings forming a part of the specification, Figure 1 is a side elevational view of a part of a railway car truck showing the invention in connection therewith. And Figure 2 is a horizontal sectional view of the construction corresponding substantially to the line 2-2 of Figure 1.

As shown in the drawings, the frame proper is of the usual rectangular formation including box-shaped side members, one of which is indicated by the reference character 10. Secured centrally of the truck frame are the usual hangers indicated at 11 which swingably carry the usual support 12 and springs 13, the springs in turn supporting the truck bolster 14 in the usual manner.

Secured to the frame proper of the truck are pedestal members, these being usually four or six in number, depending upon whether a four or six-wheeled truck is utilized. As contemplated by this invention, the pedestals are of special construction, only one of the pedestal members being illustrated in the drawings, and indicated broadly by the reference character 15, it being understood that all of the pedestals, together with the associated parts hereinafter described, are identical in construction. Each pedestal member 15 is made of longitudinally extending transversely spaced walls 16-16, forming jaws 17 and 18, and connecting portions 19, one of the latter fitting upon each side of the frame member 10. The spaced walls

16-16 are connected together by a horizontally disposed web 20 secured to the frame member 10 by means of a bolt 21, and the outer connecting portion 19 of the wall 16-16 is secured to the frame 10 by bolts 22. 60 The spaced walls 16-16 are further connected adjacent the inner vertical edges of the jaws by means of integral webs 23 and 24, which form vertically disposed journal box guide faces; the webs at their lower ends are turned outwardly as indicated at 25-25, and secured to said webs by means of bolts is a cross bar 26 adapted to detachably hold the journal box in place.

The journal box 27 is slidably disposed between the guide faces provided by the webs 23 and 24, and has the usual flanges 28-28 which bear upon the opposite sides of the jaws of the pedestal member to prevent lateral displacement of the box. The top wall of the journal box is provided with a rib 290 adapted for co-operation with a pressure transmitting member hereinafter described. The journal box is adapted to slide vertically between the jaws of the pedestal, and due to the fact that in practice the pedestals and journal boxes vary somewhat in size, considerable clearance is allowed between the side walls of the journal box and the guide faces of the pedestal, which permits a certain amount of tilting of the journal box, causing excessive wear of the guides. It is therefore important to provide means of the character now to be described for preventing excessive tilting of the box.

The jaw 18 of the pedestal is of somewhat greater width than the jaw 17, and at its lower end has an extension 29 forming a cup-shaped seat 30 adapted to accommodate the lower end of a coiled spring 31. Seated upon the upper end of the coiled spring is a follower 32, on the upper wall of which is formed a rib 33. A short bar 34 is disposed between the walls 16-16, and pivotally mounted upon a pivot pin 35 supported in said walls, the outer end of the bar being provided with a groove 36 which fits over the rib 33 on the follower 32. The guide web 24 is cut out as indicated at 37, and the inner end of the bar 34 extends to a position over the top wall of the journal box 27. The inner end of the bar is provided with a groove 38 fitting over the rib 290 on the top wall of the journal box, and bears thereon.

In operation, assuming an undulation in 110

the track causes vertical movement of the journal box 27, this movement will be transmitted to the inner end of the bar 34, which moving about the pivot 35 compresses the spring 31. During this movement of the bar, because of the connection of the inner end with the journal box, the journal box is slightly tilted in a clock-wise direction, this being permitted by the clearance usually provided between the side walls of the journal box and the guide faces of the pedestal. When the journal box returns to its normal position, the pivoted bar 34 guides the same from its slightly tilted position and normally 10 holds the journal box in vertical alignment with the guide faces of the pedestals, thereby doing away with any possibility of excessive tilting of the journal box, or of the journal box assuming a permanently tilted 15 condition.

While I have herein shown and described what I consider the preferred manner of carrying out the invention, the same is merely 20 illustrative, and I contemplate all changes and modifications which come within the scope of the claims appended hereto.

I claim:

1. In a truck of the character described, the combination with a frame having a pedestal member thereon; of a journal box vertically movable between the jaws of said pedestal; and a bar pivotally mounted on said pedestal and having one end bearing on and movably connected to said journal box; and 30 yieldable means interposed between the opposite end of said bar and a fixed abutment on said pedestal.

2. In a truck of the character described, the combination with a frame; of a pedestal member mounted thereon having jaws; a bar pivoted between its ends and rigidly sup- 35

ported with respect to said frame; said bar having one end connected to said journal box to guide the journal box in its movement and transmit the load to said journal box; and 45 yieldable means interposed between the free end of said equalizer bar and a supporting member fixed with reference to said frame.

3. In a truck of the character described, the combination with a frame; of a pedestal 50 member having spaced jaws rigidly connected to said frame; a journal box slidably mounted between the jaws of said pedestal member; a transmitting member pivotally mounted on one jaw of said pedestal and having one end movably connected to the top wall of said journal box bearing thereon; an extension rigidly connected with said pedestal member; and yieldable means interposed between said extension and the free end of 55 said transmitting member.

4. In a car truck, the combination with a truck frame; of a pedestal member fixed to the truck frame, said pedestal member having spaced guide jaws forming a guideway therebetween, one of said jaws having abutment means thereon; a journal box movable vertically between said jaws in said guideway; a pressure transmitting member; means for guiding said pressure transmitting member in a definite path, said pressure transmitting member being interengaged with said journal box to center the same between said jaws; and means interposed between said abutment and pressure transmitting member 75 for yieldingly opposing movement of the pressure transmitting member.

In witness that I claim the foregoing I have hereunto subscribed my name this 17th day of May, 1927.

JOHN F. O'CONNOR.
